UNITED STATES PATENT OFFICE.

HORATIO S. KEMP, OF MILWAUKEE, WISCONSIN.

DESIGN FOR A BUCKLE-SHIELD.

40,432.

Specification for Design.

Patented Jan. 11, 1910.

Application filed February 13, 1909. Serial No. 477,825. Term of patent 14 years.

To all whom it may concern:

Be it known that I, HORATIO S. KEMP, a citizen of the United States, residing at Milwaukee, in the county of Milwaukee and State of Wisconsin, have invented a new, original, and ornamental Design for Buckle-Shields, of which the following is a specification, reference being had to the accompanying drawing, forming a part thereof.

In the drawings Figure 1 is a plan view of a buckle shield, showing my new design; Fig. 2 is a side view thereof; and Fig. 3 is an end view thereof.

The invention consists of a buckle shield of a substantially rectangular shape with rounded edges and projecting rounded cor-

ners and with a general convexity from end to end and from side to side with depressed end portions leading to transverse slots, and having in the center of its convex upper surface a raised convex circular ornament, the inner edges of the transverse slot being curved approximately concentrically with the inner edges of the circular ornament.

I claim:

The ornamental design for a buckle shield, as shown and described.

HORATIO S. KEMP.
